US0D1086971S

(12) **United States Design Patent** (10) **Patent No.:** **US D1,086,971 S**
(45) **Date of Patent:** **** Aug. 5, 2025**

(54) **VEHICLE SENSOR ARMOR**

(71) Applicant: **JOMAX CUSTOMS LLC**, Wittmann, AZ (US)

(72) Inventor: **Mark Fountain**, Wittmann, AZ (US)

(73) Assignee: **JOMAX CUSTOMS LLC**, Wittmann, AZ (US)

(**) Term: **15 Years**

(21) Appl. No.: **29/890,026**

(22) Filed: **Apr. 19, 2023**

Related U.S. Application Data

(62) Division of application No. 29/711,726, filed on Nov. 1, 2019, now Pat. No. Des. 1,021,745.
